UNITED STATES PATENT OFFICE.

OSWALD HAASE, OF LA PAZ, BOLIVIA.

CHANGEABLE-COMBINATION LOCK.

Application filed August 12, 1924. Serial No. 731,626.

To all whom it may concern:

Be it known that I, OSWALD HAASE, a citizen of the Republic of Germany, residing at La Paz, Bolivia, South America, have invented certain new and useful Improvements in Changeable-Combination Locks, of which the following is a specification.

The present invention pertains to combination locks for safes, vaults and the like.

10 Most combination locks as heretofore constructed have the lock proper, that is, the tumblers and their associated parts, located on the inner face of the safe door in a line with, or practically in a line with, the axis 60
15 of the spindle which projects through to the outer face of the door and carries the numbered revolving disk. The location of the tumblers, or in other words, the combination, is betrayed by this fact. 65
20 As the combination is thus in direct connection with the spindle, the latter conveys to the outside of the safe certain indications as to the working of the mechanism, in fact, sufficient to enable practiced individuals 70
25 with a fine sense of touch to ascertain the combination and open the safe. If the outer numbered disk and spindle are removed, which is quite easy, and the combination forced backwards into the safe, the safe may 75
30 be opened by retracting the bolts.

My experience in opening combination lock safes of the described and other types without the use of tools for owners who have lost or forgotten their combination numbers, 80
35 has led me to devise the present device to defeat my own method of attack.

It is the purpose of this invention to provide a combination lock in which the location of the lock proper, i. e., the part which 85
40 includes the tumbler disks, is unknown to and cannot be determined by strangers without first seeing the inside of the safe door. In the present device the combination mechanism no longer lies in, or substantially in, 90
45 the axis of the operating spindle, but is located in any desired position on the inside of the door at a substantial distance from the spindle and connected thereto by means of a suitable chain and sprocket wheels. The combination mechanism therefore is not connected directly to the operating spindle and the combination disk. Thus it is impossible 95
50 for even the most practiced operator to derive any indications from the latter which 100
55 would assist him in discovering the combination, since it is obvious that the chain, by 105
110

reason of its nature, is incapable of conveying such indications.

A further object of my invention is the arrangement whereby the opening of the safe 60 door is rendered impossible even when force is used to bore or cut out the combination disk and operating spindle, which with my device would only serve to isolate the combination mechanism. 65

It is intended that my device be fitted to any existing safe door or the like, without serious alterations thereto and without screws, rivets or bolts which extend to the outer side of the door. 70

A still further object is the provision of means whereby all the numbers of the combination of the lock can be altered in one operation, a convenience not found in existing combination locks. 75

In the drawings, which represent a practical embodiment of the invention and in which like reference numerals indicate the same parts throughout the several views, 80

Figure 1 is a rear view of a safe door 80 showing my lock applied thereto, certain of the parts of the lock being removed or broken away in order to clearly disclose the construction and the arrangement of the parts when in locked position; 85

Fig. 2, a vertical sectional view taken on line 2-2 of Fig. 1, with all of the parts of the lock in place and still in locked condition;

Fig. 3, a view, similar to Fig. 1, with the parts in unlocked position;

Fig. 4, a perspective of one of the outer tumbler disks removed from the lock assembly, and

Fig. 5, a horizontal section taken on line 95 5-5 of Fig. 3.

Referring particularly to Fig. 1, the safe door 1 is provided with the usual knob 2 and number dial or face plate 3 mounted on spindle 4 in the door, whereby the tumblers of the lock may be set into the required position, according to the combination, to permit the retraction of bolts 5 and 6 by means of knob 7. Knob 7 is mounted on the outer end of a spindle 8 to the inner end of which is rigidly secured a suitable upright lever 9 having an inwardly projecting pin 10 mounted in its upper end. Pin 10 projects through a vertical slot 11 provided in the horizontal bar 12 on one end of which, near the outer edge of the door 1, is rigidly mounted the upright bar 13 carrying the 105
110

bolts 5 and 6. Members 14 and 15 secured on the inner face of door 1, near the outer edge thereof, are provided with perforated projecting ears 16 and 17, respectively, which serve as guides for bolts 5 and 6 in their locking and unlocking movements and also partially support this part of the lock mechanism.

Horizontal bar 12 is provided near its upper edge with a horizontal slot 18. Suitably mounted on the inner face of door 1 is a pin 19 having a horizontal rib or lug 20 provided on the outer end thereof and projecting inwardly through the slot 18 in member 12. Thus this end of member 12 is supported by the pin 19 on the lug 20 on which member 12 rides in locking and unlocking the lock. Member 12 is retained on pin 19 by a washer 21 and a screw 22 secured in the end of the pin. Lug 20 is of sufficient depth so that member 12 will slide freely thereon when washer 21 and screw 22 are in place.

A sprocket wheel 23 is secured against rotation on the inner end of spindle 4 by means of a pin 24 extending through corresponding perforations in the hub 25 of the sprocket wheel 23 and the spindle 4. A set screw 26 extending through a threaded opening in hub 25 of sprocket wheel 23 and engaging spindle 4 serves to further secure the sprocket wheel in place and prevent pin 24 from dropping out. A ring 27 secured to the inner face of door 1 and through which spindle 4 projects serves to suitably space sprocket wheel 23 from the inner face of door 1.

Suitably mounted at its inner end on the inner face of door 1 is a stub shaft or stud 28 having a bearing shoulder 29. On stub shaft 28 a sprocket wheel 30 is mounted for rotation, sprocket wheel 30 and the upper sprocket wheel 23 being connected by means of a suitable sprocket chain 31 whereby the lower sprocket wheel 30 may be driven by the upper sprocket wheel upon rotation of the knob 2.

Near the inner end of the horizontal member 12 there is pivotally mounted a segmental lever 32 on the reduced end 33 of a stub shaft or stud 34 which is suitably secured on the inner face of door 1. A screw 35 serves to hold lever 32 on the shaft 34 without interfering with its oscillatory movements when the lock is operated. A portion of the periphery of lever 32 is provided with a groove 36 which, when the lock is locked, serves to snugly receive the outer end of a projection 37 provided on the inner, lower part of horizontal member 12.

The lower portion of segmental lever 32 is cut away at 38 so as to provide a shoulder 39 beneath which projection 37 of member 12 may pass when lever 32 is rotated to the position shown in Fig. 3 to cause retraction

of bolts 5 and 6 during the unlocking movement. Projection 37 is beveled at 40 to permit the ready movement of the grooved edge of lever 32 over the projection 37 as the latter is withdrawn from beneath shoulder 39 and also to guide projection 37 beneath shoulder 39 when the parts move in the opposite direction. Stops 41 and 42 on the inner face of door 1 serve to limit the oscillatory movements of lever 32.

Pivots connected at one end to the lower portion of lever 32 by means of a screw 43 is a lever 44, the opposite end of which has an outwardly projecting arm 45 formed thereon and adapted to engage the notches in the tumbler disks, when the latter are properly set, to permit unlocking of the lock.

Again referring to the lower sprocket wheel 30, it will be noted that the outer hub portion thereof extends to the outer end of stub shaft 28. A screw 46 secured in the end of shaft 28 bears against this hub portion and serves to hold the sprocket wheel on the shaft. Mounted on this outer hub portion and suitably secured, as by screws, to the outer face of sprocket wheel 30 is a driving tumbler disk 47 having a number of threaded openings 48 therein in one of which is mounted a screw 49 having its head projecting from the outer face of the disk. The disk 47 is provided on its periphery with a notch 50 having an abrupt wall 51 and a curved wall 52, the purpose of which will appear later. In Figs. 1 and 3, the remaining driven tumbler disks and the associated parts are removed in order to clearly show the innermost tumbler disk 47 just described.

The lower sprocket wheel 30 and the tumbler disks are enclosed within a casing or box 53 suitably secured to door 1. The rear upper portion of casing 53 is cut away at 54 to provide for the passage of lever 44 and sprocket chain 31. A lid 55 for casing 53 is attached thereto by screws 56.

Rigidly mounted on the inner face of lid 55 is an outwardly projecting stub shaft 57. Shaft 57 is hollow at its inner end and, when lid 55 is in place, slips over the outer hub portion of sprocket wheel 30 which serves as a support for the outer end of the shaft.

Mounted to freely rotate on stub shaft 57 are a number of driven tumbler disks 58, of practically the same construction as driving tumbler disk 47. Disks 58 are notched at 59, similarly to disk 47, but are each provided with a greater number of threaded perforations 60 in two of which are mounted screws 61, 62, the former having its head projecting from the outer face of the disk and the latter from the inner face thereof (Fig. 4). Disks 58 are separated from each other on shaft 57 and from lid 55 by means of washers 63 which latter are keyed to

shaft 57 to prevent rotation of disks 58 by frictional engagement of the parts. A split spring ring 64 mounted in a groove in the outer end of shaft 57 retains disks 58 and washers 63 on the shaft.

Operation.—In the construction described, it is obvious that rotation of the knob 2 in either direction by the operator will cause rotation of the combination dial 3 and spindle 4 in the same direction, as in the ordinary form of combination lock operating mechanism. As spindle 4 revolves, upper sprocket wheel 23 is rotated with it, thereby causing lower sprocket wheel 30 to rotate in the same direction by means of the chain 31 connecting them. Tumbler disk 47, being connected to sprocket wheel 30, also revolves, during which movement screw or pin 49 on the outer face of disk 47 engages with pin 61 or screw 61 on the inner face of the tumbler disk 58 adjacent disk 47, or the first driven disk. The rotation of driving tumbler disk 47 being continued by means of further operation of knob 2 in the same direction, the first tumbler disk 58 will then be rotated therewith by reason of the engagement of pin 49 with pin 61. Rotation of the parts being continued, pin 62 on the opposite side of tumbler disk 58 will engage pin 61 on the adjacent face of the next tumbler disk 58 and so on, in the same manner, until all of the tumbler disks are picked up and rotated together. During these operations arm 45 of lever 44 rides on the peripheries of tumbler disks 47 and 58.

The pin 49 in the tumbler disk 47 and pins 61, 62 in tumbler disks 58 are, of course, located in such of the threaded openings in the disks as will correspond with the combination to be given the lock, or vice versa, so that upon revolving knob 2 back and forth in accordance with the combination, the tumbler disks 47 and 58 will finally assume positions with their notches 50 and 59 in alinement, as will be readily understood.

Assuming the mechanism is locked, it may be unlocked by rotating knob 2 in accordance with the combination. When knob 2 has been rotated next to the last time during the unlocking operation (which is a clockwise direction looking from the outside of door 1), notches 59 of tumbler disks 58 will be in alinement with each other just beneath arm 45 of lever 44. In the final movement of tumbler disk 47, which is in a counter clockwise direction, notch 50 thereof also alines with notches 59 of disks 58 beneath arm 45, which latter then drops by gravity into the notches, since lever 44 is loosely pivoted on screw 43. The movement of tumbler disk 47 being continued in the same direction, lever 44 will be shifted to the right, as shown in Fig. 3, by reason of the engagement of arm 45 with the abrupt wall 51 of notch 50

in disk 47. As arm 45 is also in engagement with the notches of disks 58, this last mentioned movement will cause them to revolve with disk 47 to the position of the latter shown in Fig. 3.

The movement of lever 44 to the right, just described, causes segmental lever 32 to swing about stud 34 from its lower position against stop 42 (Fig. 1) to its upper position against stop 41 (Fig. 3). During this movement of lever 32, the edge portion thereof provided with groove 36 will have passed out of engagement with and above projection 37 of member 12. Spindle 8 may then be revolved clockwise and through crank 9 and its pin 10 which engages with member 12 in slot 11, member 12 will be shifted horizontally to retract the bolts 5 and 6, as shown in Fig. 3. As member 12 is thus moved, projection 37 thereof moves beneath shoulder 39 of lever 32 into a position in front of the reduced portion 38 of lever 32, aided by the beveled portion 40 of projection 37. It will thus be seen that the parts will remain in the condition shown in Fig. 3, until the bolts 5 and 6 are advanced for locking purposes, as shown in Fig. 1.

To advance the bolts 5 and 6, and lock the door 1, knob or handle 7 is turned counter-clockwise, looking at the front of the door, whereupon the connected parts move in the opposite directions thereby withdrawing projection 37 of member 12 from beneath shoulder 39 of segmental lever 32. Knob 2 is then revolved in a clockwise direction which, through the connected parts, causes a corresponding movement of tumbler disk 47. Since arm 45 of lever 44 is still resting in the notches of the driving tumbler disk 47 and the driven tumbler disks 58, lever 44 will be shifted during this movement of disk 47 to its left-hand position (Fig. 1), and the driven tumbler disks 58 will revolve with tumbler disk 47 by reason of the engagement of arm 45 with the abrupt shoulders of the notches 58 in these disks.

When lever 44 shifts to the left, segmental lever 32 is rotated thereby to its lower position against stop 42 (Fig. 1), the channelled peripheral portion of lever 32 engaging with the outer end of projection 37 of member 12 to prevent retraction of the bolts.

Rotation of knob 2 and consequently driving tumbler 47 is continued which results in arm 45 of lever 44 riding up the curved wall 52 of the notch in disk 47 and on to the periphery thereof (Fig. 1). Continuing in its movement in the same direction, driving tumbler disk 47 picks up the driven tumbler disks 58 one after another, as heretofore explained, until all of the tumbler disks are rotating in unison with their notches out of

alinement and arm 45 of lever 44 riding on their peripheries. The mechanism is then locked and can be unlocked only by using the correct combination of settings of dial 3.

5 With the combination described, it will readily be seen that the location of the tumbler mechanism and the associated parts cannot be ascertained from the outside of the door 1, since the mechanism may be located in the position illustrated or at any other place on the inner face of the door, a longer chain 31 being used if necessary in order to place the mechanism in a position remote from the knob 2 and spindle 4. The 10 size, shape and arrangement of the bolt throwing mechanism may also be varied to accommodate any location of the other parts of the device.

It is obvious that the entire combination 20 of the lock may be changed in one operation simply by altering the setting of one of the sprocket wheels 23 or 30 on its shaft. This may be readily accomplished by removing chain 31 from one of the sprocket wheels, 25 resetting the wheel, and then replacing the chain.

It is contemplated that other changes may be made, and the invention is therefore not intended to be restricted to the means shown 30 except as limited by the appended claims.

What is claimed is:

1. In a combination lock, the combination of an operating spindle; a sprocket wheel mounted on said spindle for rotation therewith; a second sprocket wheel; tumbler mechanism associated with and adapted to be operated by rotation of said second-mentioned sprocket wheel; and a sprocket chain connecting said sprocket wheels.

40 2. In a combination lock, the combination of a support; an operating spindle mounted for rotation therein; a sprocket wheel mounted on the inner end of the spindle for rotation therewith; a stud mounted on said support; a second sprocket wheel mounted for rotation on said stud; a sprocket chain connecting said sprocket wheels; and tumbler mechanism associated with and adapted to be operated by rotation of said second-mentioned sprocket wheel.

50 3. The combination in a permutation lock of operating means comprising a spindle, an operating knob and number dial on one end thereof, and a sprocket wheel fixedly mounted on the opposite end of the spindle; tumbler mechanism; a second sprocket wheel associated with and adapted to operate said tumbler mechanism upon rotation thereof; and a sprocket chain connecting said sprocket wheels.

60 4. In a combination lock, including an operating spindle, a number dial therefor, and a tumbler mechanism located remotely with reference to said operating spindle, a sprocket wheel and sprocket chain driv-

ing mechanism connecting said operating spindle and said tumbler mechanism.

5. A combination lock comprising, in combination, a rotative operating spindle; a sprocket wheel mounted on said spindle for rotation therewith; a tumbler mechanism; a second sprocket wheel associated with and adapted to operate said tumbler mechanism upon rotation thereof; and a sprocket chain connecting said sprocket wheels, the setting of said first-mentioned sprocket wheel in its plane of rotation on the operating spindle being adapted for alteration to change the entire combination of the lock.

6. In a combination lock, the combination of a support; an operating spindle mounted for rotation in said support; a sprocket wheel mounted on said spindle for rotation therewith; tumbler mechanism mounted on said support; a second sprocket wheel associated with and adapted by rotation thereof to operate said tumbler mechanism; and a sprocket chain connecting said sprocket wheels, the driving relation of said sprocket wheels with reference to each other being adapted to be altered to change the entire combination of the lock.

7. A combination lock comprising, in combination, a safe door; an operating spindle mounted for rotation therein; a number dial mounted on one end of said spindle for rotation therewith; a sprocket wheel mounted on the opposite end of said spindle for rotation therewith; bolt mechanism for said door; bolt operating mechanism; tumbler mechanism mounted on the door remote from said operating spindle; a second sprocket wheel associated with and adapted upon rotation thereof to operate said tumbler mechanism; a sprocket chain connecting said sprocket wheels; and means for preventing and permitting the actuation of the bolt operating mechanism, said means being controlled by the tumbler mechanism.

8. A combination lock comprising, in combination, a safe door; an operating spindle mounted for rotation therein; a number dial fixed on one end of said spindle; a sprocket wheel fixed on the opposite end of said spindle; tumbler mechanism mounted on said door at a distance from the operating spindle; a second sprocket wheel associated with and adapted upon rotation thereof to actuate said tumbler mechanism; a sprocket chain connecting said sprocket wheel; bolt mechanism; and means, controlled by said tumbler mechanism, for permitting and preventing operation of said bolt mechanism, the driving relation of said sprocket wheels with reference to each other being adapted to be altered to change the entire combination of the lock.

In testimony whereof I have signed my name to this specification.

OSWALD HAASE.
